UNITED STATES PATENT OFFICE.

CARL RUDOLPH RING, OF IRON MOUNTAIN, MICHIGAN.

COASTER.

Application filed July 30, 1927. Serial No. 209,469.

This invention is a toy vehicle and has for its object the provision of a simple, strong and durable toy upon which a child may be seated and may coast or slide upon snow or ice. The invention provides an inexpensive toy which may be readily steered and upon which the rider may easily remain upright and keep his balance. The invention is illustrated in the accompanying drawing and 10 will be hereinafter fully set forth.

In the drawing:

Figure 1 is a side elevation of a toy embodying the invention;

Fig. 2 is a plan view of the same, partly 15 broken away and in section;

Fig. 3 is an enlarged detail section on the line 3—3 of Fig. 1, and

Fig. 4 is an enlarged detail section on the line 4—4 of Fig. 1.

20 In carrying out the invention, there is provided a runner 1 which consists of a narrow flat bar of metal having its front end up turned, as shown at 2, to provide an ornamental terminal for the runner and also 25 project above the ground an appreciable distance so that it will serve also as a tender to turn aside small objects which might otherwise act to upset the device. All tendency of the runner to dig into the ground is, of course, avoided. The rear extremity of the runner is also given an ornate finish by being turned into a coil, as indicated at 3. Through 30 the straight length of the runner, a reinforcing rib 4 is provided on the upper side thereof and the said rib extends longitudinally from the lower point of the front curve 2 to the lowest point of the rear curve 3, the entire runner being of spring steel so that it may be flexed laterally for steering. Adjacent the front end of the rib 4, there is secured a post 5 which is preferably inclined upwardly and rearwardly somewhat, as clearly shown in Fig. 2, the lower end of the post being notched so that it will fit over the 45 rib and may be riveted thereto. At the upper extremity of the post is a T-fitting 6, through the head of which is inserted a handle bar 7 which has its ends extending rearwardly in divergent relation and which may 50 be firmly secured in the fitting in any desired manner. Immediately below the fitting 6, a bracket 8 is provided, the said bracket defining a central eye or loop 9, which encircles the post, and leaves 10 which 55 are brought together at the back of the post and extend rearwardly therefrom with their

opposed faces in contact. A backbone 11 is provided and the front end of the same is longitudinally notched so as to span the leaves 10 and be riveted thereto, as indicated 60 at 12, while the rear end portion of the backbone is curved downwardly and is notched at its extremity whereby it may span the rib 4 and be firmly riveted thereto, as indicated at 13.

65 At the bend or curve of the backbone, a collar 14 is fitted around the same and secured thereto by a rivet or similar device 15 and from the front end of this collar a saddle arm 16 rises and is then carried backwardly, as clearly shown in Fig. 1, to support the saddle or seat 17 which may be of any appropriate form and secured to the saddle arm 16 in any desired manner.

70 Below the backbone, a brace 18 is provided and this brace has its front end rigidly secured to the leaves 10 of the bracket 8 and its rear end fitted over and rigidly secured to the rib 4 in advance of but near the backbone. The brace reinforces the structure and supplements the post 5 and the backbone in preventing collapse of the device. At a suitable point in the length of the brace 18, a foot rest 19 is secured thereto, and this foot rest consists of a strap or bar 80 having its central portion formed into a loop or collar 20 which spans the brace and may be clamped thereto by a set screw 21, as shown most clearly in Fig. 3. From the sides of the loop or collar 20, steps 22 project laterally and have stop lugs 23 at their outer extremities.

85 The eye or loop 9 permits a pivotal or turning movement of the post 5 and a lug or shoulder 25 on the post immediately below the loop prevents downward movement of the loop.

90 The child using the toy sits astride of the seat 17 with his feet upon the rest 22 and the lugs 23 will serve to hold the feet upon the rest, this position being safer than that most frequently assumed in using the ordinary sled. A slight impulse being given the coaster, it will proceed on a down grade until it reaches a level surface and will proceed 100 over the level surface until it loses its momentum. The device when in motion will naturally tend to remain in upright position and the handle bars 7 provide a convenient grip for the user so that he may 105 retain his position upon the seat and also control the coaster. By turning the handle

bar to one side, the runner will be flexed and the device properly steered, the foot rests furnishing a purchase for the rider in steering. The arrangement of the rear ends of the backbone and the brace, relative to the steering post, provides for flexing of the runner without any loss of strength.

It will be noted that I have provided an exceedingly simple device which may be produced at a low cost and which will be strong and durable. When not coasting, the device may be easily carried and as it is supported upon only a single runner more skill will be required to steer it than is required in the use of an ordinary sled so that the child will derive more pleasure from the use of this device than from the use of the ordinary sled and will also intuitively acquire a finer sense of balance and direction. As there is very little friction, there is no appreciable loss of speed by the runner cutting into snow.

Having thus described the invention, I claim:

25 1. A coaster comprising a single runner, a post secured to and rising from the front end of the runner, a backbone secured to the runner near the rear end thereof and extending upwardly and then forwardly therefrom,

a handle bar carried by the upper end of the post, a saddle on the backbone, a bracket having a loop portion encircling the post immediately below the upper end of the same and a rearwardly extending portion rigidly secured to the front end of the backbone, and a brace secured at its front end to the said bracket below the front end of the backbone and at its rear end to the runner in advance of the rear end of the backbone. 30 35

2. A coaster comprising a single runner, a post secured to and rising from the front end of the runner, a backbone secured to the runner near the rear end thereof and extending upwardly and then forwardly therefrom, a handle bar carried by the upper end of the post, a saddle on the backbone, a bracket having a loop portion encircling the post immediately below the upper end of the same and a rearwardly extending portion rigidly secured to the front end of the backbone, a brace secured at its front end to the said bracket below the front end of the backbone and at its rear end to the runner in advance of the rear end of the backbone, and a foot rest secured upon the said brace. 40 45 50 55

In testimony whereof I affix my signature.

CARL RUDOLPH RING. [L. S.]
